POLISH ROD CLAMP

Ira Naylor and Burl Yost, Winegars, Mich.

Application May 20, 1938, Serial No. 209,129

2 Claims. (Cl. 24—243)

This invention relates to clamps, more particularly to clamps for use in connection with polish rods for supporting a string of sucker rods in oil well pumping apparatus.

5 Due to the jarring conditions under which polish rod clamps operate they are apt to become loosened with resultant loss of the sucker rods. With this disadvantage in mind an object of the present invention is to provide a polish rod clamp 10 which may be readily applied to and removed from the polish rod and when in applied position will positively grip the rod so that jarring strains cannot dislodge the clamp.

15 A further object is to provide a clamp of this type which will be formed of a few strong and durable parts, which will be inexpensive to manufacture and which will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of 25 the advantages of the invention.

In the accompanying drawing forming part of this specification,

Figure 1 is a longitudinal sectional view of a 30 polish rod clamp constructed in accordance with the invention.

Figure 2 is a cross sectional view of the clamp taken on the line 2—2 of Figure 1 and showing the clamp about to be applied to a polish rod.

Figure 3 is a cross sectional view of the clamp 35 showing the clamp applied to the polish rod.

Figure 4 is a perspective view of the core and head of the clamp.

Figure 5 is a perspective view of the body of the clamp.

40 Figure 6 is a perspective view of the jaw of the clamp.

Figure 7 is a side elevation of the clamp with parts broken away.

Referring now to the drawing in which like 45 characters of reference designate similar parts in the various views, 10 designates the body of the clamp, the same being of hollow cylindrical formation and provided at one side with a handle 11, best shown in Figure 7. Opposite the handle 50 the body is provided with an opening 12 extending the entire length of the body and adapted to permit the body to be slid laterally on to the polish rod 13, as best shown in Figure 2.

The body is provided in its inner wall with a 55 longitudinal groove 14 best shown in Figure 5

and mounted in this groove is a jaw 15, best shown in Figure 6. The jaw is in the nature of a bar having concave face 16 which may be plain or corrugated as desired. A screw 17 is engaged through an opening 18 in the body, as best shown in Figure 1, and is threadedly engaged in an opening 19 in the jaw to secure the jaw to the body for movement in a radial direction for application to and release from the polish rod 13. A helical spring 20 is sleeved upon the screw and is confined under tension between the head of the screw and the inner wall of an opening 21 in the body, in which the spring is seated. The purpose of the spring is to withdraw the jaw from the sucker rod when the clamp screws 22 are 15 loosened.

The clamp screws 22 are threadedly engaged in openings 23 formed in the body above and below the opening 18. These screws bear against the rear face of the jaw and when tightened move 20 the jaw readily against the tension of the spring 20 to tightly bind the concave face of the jaw against the side of the polish rod, as best shown in Figure 3.

A core 24 is rotatably mounted within the body 25 and is provided at the upper end with a disc-like head 25 which is supported upon the top of the body, as best shown in Figure 1. The core is equal in length to the body, and it and the head are provided with aligned slots 26 and 27, which, 30 in one position of these parts, register with the opening 12 in the side of the body. When the slots are in registration with the opening the clamp may be slipped laterally on to the polish rod. After the application of the clamp to the 35 polish rod the head and core are turned to move their slots out of registration with the opening in the body and thereby prevent the lateral displacement of the clamp from the polish rod.

The head 25 is provided with a handle 28 40 through the medium of which it and the core may be turned. Turning movement of the core is limited by a screw 29 carried by the body and fitting in an arcuate groove 30 formed in the core.

Since the operation of the clamp has been 45 described as the description of the parts progressed it is thought that the invention will be fully understood without further explanation.

What is claimed is:

1. A polish rod clamp comprising a hollow 50 cylindrical body having a longitudinal slot in one side extending from end to end of the body to permit the body to be slipped laterally on to a polish rod, the body being provided on the inner wall with a longitudinal groove extending from 55

- end to end of the body, a clamping jaw seated in said groove, a screw slidably fitted in the body and connected to the jaw for supporting the jaw in position, a spring sleeved on the screw and engaging the body, said spring constantly tending to urge said jaw into said longitudinal groove, screws 5 threadedly engaged with the body on opposite sides of the first named screw and adapted to be advanced against the jaw to move the jaw into clamping engagement with the polish rod, a core 10 rotatably mounted within the body and having a longitudinal slot in one side adapted to align with the slot in the body at one limit of movement to receive the polish rod and adapted to align with said longitudinal groove in the body at the 15 opposite limit of movement to permit said jaw to pass into the core and engage the polish rod, and means on the core and body permitting relative rotary movement of the core and body.
- 20 - 2. A polish rod clamp comprising a hollow cylindrical body having a longitudinal slot in one side extending from end to end of the body to permit the body to be slipped laterally on to a polish rod, the body being provided on the inner 25 wall with a longitudinal groove extending from end to end of the body, a clamping jaw seated in

said groove, a screw slidably fitted in the body and connected to the jaw for supporting the jaw in position, a spring sleeved on the screw and engaging the body, said spring constantly tending to urge said jaw into said longitudinal groove, screws 5 threadedly engaged with the body on opposite sides of the first named screw and adapted to be advanced against the jaw to move the jaw into clamping engagement with the polish rod, a core 10 rotatably mounted within the body and having a longitudinal slot in one side adapted to align with the slot in the body at one limit of movement to receive the polish rod and adapted to align with said longitudinal groove in the body at the 15 opposite limit of movement to permit said jaw to pass into the core and engage the polish rod, a head on the core bearing against the top of the body, a handle on said head, a handle on said body, there being an arcuate groove formed in the outer wall of said core, and a screw engaged 20 through said body and entering said arcuate groove for limiting rotary movement of the core relatively to the body.
